FLASHLIGHT

Walter R. Kopp, New Haven, Conn., assignor to
 Western Cartridge Company, New Haven,
 Conn., a corporation of Delaware

Application November 3, 1939, Serial No. 302,635

3 Claims. (Cl. 240—10.6)

This invention relates to hand lamps and more particularly to an improved means for mounting a lamp bulb of the prefocused type in the reflector of a hand lamp.

In the old type of portable hand lamp a bulb was employed having a threaded stem which was received in a socket mounted adjacent the head end of the lamp casing. A reflector was also arranged in the end of the casing and this reflector was provided with an opening through which the lamp bulb projected. Due to the threaded connection between the lamp bulb and its support, the arrangement of the lamp bulb in focus with the reflector was not always maintained. Any wearing of the threads or any variation in tightening the lamp bulb in its socket would shift its position axially of the hand lamp casing and therefore move it with respect to the reflector.

A recent development in a portable hand lamp construction includes the use of prefocused bulbs. Such bulbs are provided with an unthreaded stem and with a flange or shoulder surrounding the stem. The lamp bulb is inserted through the opening in the reflector with the stem projecting rearwardly from the opening and it is retained in position by engagement of the flange or shoulder with a seat arranged at the rear side of the reflector opening. The opposite side of the flange or shoulder on the lamp bulb stem is engaged by suitable means for retaining the shoulder or flange against its seat.

An object of the present invention is the provision of simple and inexpensive means for retaining a prefocused lamp bulb in position with respect to the reflector and permitting it to contact with the center electrode of the upper cell of a battery arranged in the flashlight casing. For this purpose I provide an externally threaded member on the inner end of the reflector and further provide a threaded cup which is adapted to engage this member and which is provided with a central portion having an opening therein for the passage of the lamp bulb stem and having a portion surrounding the opening which engages the flange or shoulder on the lamp bulb stem to retain it against the seat formed on the inner side of the reflector opening.

In the accompanying drawing I have shown several embodiments of the invention. In this showing:

Fig. 1 is a sectional view of the end of a hand lamp casing showing the invention applied to a die cast reflector;

Fig. 2 is a plan view of the bulb holding cup;

Fig. 3 is a sectional view of a stamped reflector having threaded means for engagement with the cup;

Fig. 4 is a similar view of the reflector before the threaded means is secured thereto; 5

Fig. 5 is a similar view of the threaded means; and

Fig. 6 is a plan view of the threaded means.

Referring to Fig. 1 of the drawing, the reference numeral 1 designates generally a portion 10 of a hand lamp casing having a flared upper end 2 and having a battery arranged therein composed of one or more cells, the end of the upper cell being shown at 3. This cell is provided with a central electrode 4 which is adapted to be engaged by the base terminal of a lamp bulb in the usual manner. The enlarged head of the casing is threaded as at 12' and is provided with a flange 6. A reflector 7 is provided with a peripheral flange 8 which is adapted to be supported by the flange 6. A ring 9 of insulating material may be arranged between the flanges 6 and 8. A lens 10 is arranged on the flange 8 of the reflector and may be surrounded by a strip 11 of insulating material. The reflector and the lens are retained in position by an end cap 12 which is internally threaded at 5 to engage the threads 12' on the end of the casing. 20

In the form of the invention shown in Fig. 1 of the drawing, the reflector 7 is die cast and 30 is provided with an externally threaded cylindrical boss 13 at its inner end. It is also provided with a seat 14 for a lamp bulb of the prefocused type. As shown lamp bulb 15 is provided with a stem 16 having a flange or shoulder 17 which engages the seat 14. The threaded boss 13 is adapted to support an internally threaded cup shaped member 18 which retains the lamp bulb on its seat and thereby prevents relative movement of the lamp bulb and reflector. As 35 shown, the base of the cup shaped member is inclined inwardly and upwardly as at 19 terminating in an inner cylindrical portion 20 which is of greater diameter than the stem of the lamp bulb. The upper end of this cylindrical portion 20 is provided with an inwardly extending flange 21 which engages one side of the flange or shoulder 17. The lamp bulb is provided with the usual base terminal 22 which engages the 40 central electrode 4 and a suitable switch arm 23 is adapted to engage the cup shaped member 18 when in operative position to complete the circuit from the battery to the filament. The switch member 23 may be controlled by any suit- 45

50

55

able switch mechanism (not shown) on the flashlight casing.

In the form of the invention shown in Figs. 3 to 6 of the drawing, I employ a cup shaped member 18 for retaining the bulb in position but in this form of the invention I employ a stamped reflector 24 and secure an externally threaded member 25 thereto. The externally threaded member cooperates with the cup shaped member 18 to support the bulb in position in the same manner as the threaded boss 13 of the reflector 7 shown in Fig. 1 of the drawing. The reflector is provided with a flange 26 at its outer end which functions similarly to the flange 8 to retain the reflector in position in the lamp casing. A neck 27 surrounds the central opening 28 of the reflector and at the juncture of the neck and the body of the reflector I provide a plurality of ribs or indentations 28'. The threaded member 25 is provided with an inturned flange 29 at its lower end. A sleeve 30 is secured to this flange by crimping it above and below the flange as indicated at 31 and 31'. The upper end of the sleeve is provided with an annular inwardly extending flange 32. After the threaded member 25 and the sleeve have been assembled, the parts are assembled with the reflector proper as shown in Fig. 3 and the neck 27 is spun over the flange 32 as indicated at 33 to secure the members to each other. The inner surface of the flange 32 is provided with spaced notches 34 corresponding in number to the ribs or indentations 28' and the ribs are received in these notches to prevent relative rotational movement of the members after they have been assembled.

When the neck 27 is spun over the flange 32, it forms a seat, similar to the seat 14 of the die cast reflector which is adapted to be engaged by the upper side of the flange 17 of the lamp bulb. The cup shaped member 18 is then secured to the member 25 by means of the cooperating threads and flange 21 engages the lower side of flange 17 on the stem of the lamp bulb to retain the lamp bulb in position in the manner previously described.

The construction thus provides a very simple method of supporting a prefocused lamp bulb in position in a reflector of a hand lamp and permits the base terminal 22 of the bulb to make direct contact with the central terminal of the

battery without the provision of intervening contact members. The invention may be applied to either a die cast reflector which may be threaded for the reception of the lamp bulb supporting member or to a stamped reflector in which case the threaded cooperating member 25 is secured to the reflector 24 as heretofore described or in any other suitable manner.

I claim:

1. A hand lamp comprising a reflector having a central opening therein and having a seat formed in said opening, a lamp bulb mounted in the reflector in alignment with the opening with the stem of the bulb projecting through the opening, the stem of the bulb being provided with a projecting portion engaging said seat, and a cup shaped member secured to the reflector and having a central opening for the passage of the stem, said cup shaped member having an inner cylindrical flanged portion engaging the projecting portion of the stem to retain the bulb on said seat.

2. A hand lamp comprising a reflector having a central opening therein and having a threaded cylindrical portion surrounding the opening, a lamp bulb mounted in the reflector with the stem of the bulb depending therefrom and projecting rearwardly from the opening, the stem of the bulb being provided with a projecting portion engaging the reflector, a cup shaped threaded member secured to the threaded cylindrical portion of the reflector and having a central opening for the passage of the stem of the lamp bulb, and an inner cylindrical flanged portion formed on the cup shaped member to engage the projecting portion of the lamp bulb to retain it in position.

3. A hand lamp comprising a reflector having an opening therein, a lamp bulb mounted in the reflector in alignment with the opening with the stem of the bulb projecting through the opening, the stem of the bulb being provided with a projecting portion engaging the reflector, and a cup shaped member secured to the reflector, said cup shaped member having an inner cylindrical portion through which the stem of the bulb projects, and a flange formed on the end of said cylindrical portion to engage the projecting portion on the stem of the bulb and retain the bulb in position.
